FIG. 2.

7 18

Inventor

JAMES INGELS.
By Atty N. Dubois.

UNITED STATES PATENT OFFICE.

JAMES INGELS, OF SPRINGFIELD, ILLINOIS.

RADIATOR.

1,403,784.

Specification of Letters Patent. Patented Jan. 17, 1922.

Application filed July 21, 1920. Serial No. 397,906.

To all whom it may concern:

Be it known that I, JAMES INGELS, a citizen of the United States, residing at Springfield, in the county of Sangamon and State 5 of Illinois, have invented a new and useful Radiator, of which the following is a specification.

The invention relates to radiators such as are used in conjunction with gasoline engines, or the like. Such radiators, as hitherto commonly constructed, comprise a 10 large number of permanently attached tubes, usually soldered in the radiator and a large number of radiator plates, or fins, 15 also soldered in the radiator. The tubes are subject to bursting by freezing, and the tubes and the plates are frequently injured or broken in accidental collisions. By reason of the parts being permanently united, 20 as stated, it is very difficult to repair or replace the broken parts. Only a skilled mechanic can do the work properly and at best the making of repairs and replacements is slow and consequently costly.

25 Prime purposes of the present invention are to provide a radiator having tubes which may be inserted or removed without disturbing the plates or fins and without disturbing other permanent parts of the structure; and 30 to provide other improved structural details as will hereinafter appear.

With these ends in view the invention consists in the novel features of construction and combinations of parts shown in 35 the annexed drawing, to which reference is hereby made, and which will now be described and recited in the claims.

Figure 1 is a combined front elevation and partial vertical sectional view of a 40 radiator embodying my invention. Fig. 2 is a horizontal section on the line 2.2 of Fig. 1 looking downward. Fig. 3 is a greatly enlarged fragmentary vertical section through the radiator on the line 3.3 of Fig. 1 and shows details of one tube and its 45 connections; Fig. 4 is an enlarged horizontal section on the line 4.4. of Fig. 1, looking downward, and shows in detail a fragment of one diaphragm. Fig. 5 is a combined 50 elevation and sectional view, showing keepers of modified construction; and Fig. 6 is a transverse section on the line 6.6. of Fig. 5.

The same reference numerals designate the same parts in all the views.

The radiator comprises an upper water 55 box 5, a lower water box 6, hollow columns 12 intercommunicating between the boxes 5 and 6; upper perforated plates 7, lower perforated plates 8, water tubes 9 in communication with the interior of the boxes 5 60 and 6 through the perforations of the plates 7 and 8, rods 13 connecting the plates 7 and 8, and diaphragms 10, spaced apart from each other and directing the flow of air around the tubes. 65

The water box 5 is preferably a metal casting, open at its lower end and having a flange 14, extending entirely around the lower part of the box. The box 5 has a tubular neck 15 to admit water to the box and 70 a screw cap 16 closing the neck.

The water box 6 is preferably a metal casting open at its upper end and having a flange 17 extending entirely around the upper part of the box. 75

A flat perforated metal plate 7 is conformed to the contour of the flange 14. A gasket 25 is between the plate and the flange. Bolts 18 extend through the flange and the plate and detachably connect them with each 80 other. The gasket prevents leakage of water between the connected parts.

A flat, perforated, metal plate 8 is conformed to the contour of the flange 17. A gasket 26 is between the plate and the flange. 85 Bolts 19 extend through the flange, the gasket and the plate and detachably connect them with each other. The gasket prevents leakage of water between the connected 90 parts.

The plate 7 has a series of integral tapered nipples 21, corresponding to the number of tubes 9 in the radiator, and also has openings 20 intercommunicating between the box 5 and the columns 12. 95

The plate 8 has a series of internally-screw-threaded holes 27 (Figs. 1 and 3,) corresponding to the tubes 9, and also has openings 31 intercommunicating between the columns 12 and the box 8. Tapered nipples 28 screw into the holes 27 and have polygonal heads 29 on which a wrench may be used to rotate the nipples. Lock nuts 30 are screwed on the respective nipples before the nipples are screwed into the holes, 100 and when the nipples are properly adjusted the nuts will be tightened to lock them in place. 105

The box-like columns 12 have flat ends accurately fitted to the lower face of the plate 7 and the upper face of the plate 8. Screw-threaded rods or bolts 13 firmly unite

5 the parts 7, 12 and 8, but admit of separating the parts when necessary. The rods 13, in conjunction with the tubular spaces 22 firmly unite the diaphragms 10 and keep them in proper spaced relation to each other 10 but admit of separating them when necessary.

Each diaphragm has holes 31 (Fig. 4) accommodating the respective rods 13 and holes 23 accommodating the respective tubes

15 9. The diaphragms are of very thin sheet brass. The holes 23 may be made by any suitable instrument (not shown) which will perforate the metal just as the tapered end of a pencil will perforate a sheet of paper, 20 and will form a series of springy fins 24 marginal to the hole. The middle parts of the fins 24 tend slightly towards the centre of the hole 23 so that the circumference bounded by the central parts of the fins is 25 in each instance somewhat less than the outer circumference of the tube 9 occupying the hole; it is obvious therefore, that when the tube is in place in the hole the fins will be under stress and will prevent vibration 30 of the tube in the hole but will yield to permit insertion or retraction of the tube, as the case may be. I prefer to use springy keepers integral with the diaphragm but other suitable keepers may be used without 35 departure from my invention; such, for example, as separate springs 24' (Figs. 5 and 6) attached to the diaphragm 10 and adapted to engage on the periphery of the tube 9 to prevent vibration of the tube and 40 permit easy insertion or withdrawal of the tube. Keepers of other and different forms will readily occur to persons skilled in the art and need not be detailed here.

To assemble the parts, the rods 13 will 45 be placed in position in the holes 31 of the plate 7; the box 5 will be connected with the plate by the bolts 18; the successive spacers 22 and diaphragms 10 will be placed on the rods 13 and the nuts 32 abutting against the 50 spacers adjacent to the lower ends of the rods will be tightened to hold together the associated diaphragms and spacers; the tubes 9 will be inserted through the holes 23 in the diaphragms in such position that the 55 tapered ends of the nipples 21 will occupy the upper ends of the respective tubes; the screw-threaded nipples 28 will be screwed into the respective holes 27; the columns 12 will be placed in proper position relative to 60 the plates 7 and 8 and the nuts at the lower ends of the rods will be tightened to firmly unite the parts 7, 12, and 8. The nipples 28 will then be adjusted to cause water-tight 65 juncture of the ends of the tubes with the upper and lower nipples and the lock nuts

30 will be tightened to keep the tubes and nipples in their adjusted position. The box 6 will then be attached to the plate 8 by the bolts 19.

In order to remove a broken or defective 70 tube it is only necessary to detach the box 6 from the plate 8; whereupon the tube may be pulled outwardly through the holes 23 and 27 and after it is repaired may be pushed inwardly and secured in its original position; or a new tube may be substituted if necessary, and all may be easily and quickly done without disturbing the other tubes or the diaphragms 10.

To replace a broken or damaged diaphragm the intervening diaphragms and spacers will be removed in succession from the rods 13 until the broken or damaged diaphragm is reached; it will then be taken out and repaired, or a new diaphragm substituted; the other diaphragms and spacers will then be put back in their original order and the plate 8 and the box 6 will again be attached and secured.

80 It is to be noted that the tubes 9 and the columns 12 admit of free circulation of water from one box to the other. It is to be noted further that any tube may be detached without disturbing the diaphragms and without disturbing any other tube, and that any diaphragm may be detached without disturbing any tube.

85 To the best of my knowledge and belief, I am the first to devise and use in a radiator for gasoline engines, or the like, demountable tubes in conjunction with demountable diaphragms; I therefore do not limit my claims to the precise structural details shown or described, inasmuch as minor modifications may be made within the scope of the 90 appended claims.

95 Having fully described my invention and the mode of its use, what I claim as new and desire to secure by Letters Patent is:

100 Claims.

1. In a radiator, the combination of upper and lower water boxes each having a series of nipples; a series of diaphragms each having a series of holes in line with the respective nipples and a plurality of springy 105 keepers adjacent to the respective holes; and tubes occupying the holes of said diaphragms and held by said nipples and said springy keepers.

110 2. In a radiator, the combination of upper and lower water boxes each having a series of nipples; a series of diaphragms each having a series of holes and keepers at the margins of the respective holes; and tubes occupying holes of said diaphragms and held 115 by said nipples and said keepers and inter-communicating with said water boxes.

120 3. In a radiator, the combination of a first perforated plate having tapered nipples; a second plate having internally screw- 125

threaded holes; screw-threaded nipples adjustable in the holes in said second plate; lock nuts on said screw-threaded nipples, and tubes each held by a nipple on said first plate and a nipple adjustable in said second plate.

In witness whereof I have hereunto

signed my name at Springfield, Illinois, this 14th day of July, A. D. 1920.

JAMES INGELS.
